UNITED STATES PATENT OFFICE.

JOHN R. HAMPEL, OF MILWAUKEE, WISCONSIN.

DESIGN FOR LEATHER.

Application filed August 27, 1923. Serial No. 7,097. Term of patent 14 years.

To all whom it may concern:

Be it known that JOHN R. HAMPEL, a citizen of the United States, residing at Milwaukee, in the county of Milwaukee and State of Wisconsin, has invented a new and useful and ornamental Design for Leather, of which the following is a specification, reference being had to the accompanying drawing, forming a part thereof.

The drawing is a plan view of a piece of leather embodying my new design.

I claim:

The ornamental design for leather as herein shown.

JOHN R. HAMPEL.

In presence of—

JAMES T. GUY,
W. C. FERRIS.
